UNITED STATES PATENT OFFICE

1,941,625

DARK SLIDE

Willy Salchow, Berlin-Tempelhof, Germany

Application March 3, 1932, Serial No. 596,505,
and in Germany November 30, 1928

14 Claims. (Cl. 95—34)

My invention relates to dark slides for photographic apparatus. It is particularly suitable for apparatus for photographing what is known as "copy", i. e., letters, documents, maps, book 5 pages and the like, but may be used for any other purpose, if desired. An apparatus for photographing "copy" is described in my application for patent of the United States, Serial No. 564,363, filed September 2, 1931, for "Photographic apparatus". It comprises a copy holder which is normally horizontal and an objective by which the image of the copy is projected vertically onto a mirror and reflected horizontally onto a vertical sensitized web of paper or the like in the dark 10 slide.

The dark slide according to the present invention is equipped with the usual vertical slideable covering plate in combination with means for feeding the sensitized paper to be exposed 20 by, and in time with, the movement of the covering plate. Means of this kind are described in another copending application for patent of the United States, Serial No. 567,625, filed by me October 8, 1931, for "Dark slide for photographic 25 apparatus". In this apparatus a feeding mechanism including a feeding cylinder with means for rotating it, and mechanism operatively connected to the feeding mechanism for reciprocating the covering plate are provided.

It is an object of my invention to provide a simpler mechanism which is particularly suitable for comparatively cheap apparatus.

To this end, in combination with the means for reciprocating the covering plate, I provide a gripper which is operatively connected to the reciprocating means and adapted to engage the sensitized paper upon the descent, and to release it upon the ascent, of the covering plate.

In the drawings affixed to this specification and 40 forming part thereof a dark slide embodying my invention is illustrated diagrammatically by way of example.

In the drawings

Fig. 1 is a central vertical section of the dark 45 slide.

Fig. 2 is a horizontal section on the line II—II in Fig. 1.

Fig. 3 is a vertical section on the line III—III in Fig. 1.

Fig. 4 is a central vertical section of the dark 50 slide which is similar to the section in Fig. 1 but is drawn to a larger scale and shows only a portion of the lower front end of the dark slide.

Fig. 5 is a section on the line V—V in Fig. 4.

Fig. 6 is a detail of the handle by which the

dark slide and the gripper are operated, and its accessories.

Fig. 7 is an elevation showing the dark slide attached to the rear end of a photographic apparatus, and a collector attached to the dark 60 slide at its bottom, and

Fig. 8 is a similar elevation showing a desensitizing tank attached to the dark slide.

Referring now to the drawings, and first to Fig. 7 for the general arrangement, 2 is a portion of a photographic apparatus, 3 is one of its legs, 1 is the dark slide which is fitted to the rear end of the apparatus 2 by means which will be described hereinafter, and 7 is a collector which is attached to the bottom of the dark slide by 70 strips 105.

The dark slide will now be described in detail with reference to Figs. 1—5. 105a are strips or guides at its front end by which it is detachably connected to the photographic apparatus 2. 31 is 75 the covering plate which is mounted to slide in suitable guides at the rear of the strips 105a, 49 is a sill on which bears the lower end of the covering plate 31 in its closed position, preferably with a strip of felt 49a between the plate and the sill for 80 keeping out daylight, 50 is an outer transverse bar near the top of the dark slide behind which the covering plate 31 moves, and 51 is an angular transverse covering member at the upper edge of the plate 31 which moves with the plate and bears 85 on the transverse bar 50 in the closed position of the plate 31. 52 is an inner transverse bar which extends at the rear of the covering plate 31 and at the level of the angular member 51 but is secured to the dark slide. 68 is a cover for the rear 90 and upper portions of the dark slide which is mounted to rock about a hinge 72 at its base and at its top has a jib 73 fitting a shoulder at the inner transverse bar 52. 10 is an inclined mirror on the top plate of the cover 68.

95 53 is a bracket which is attached to the inner face of the covering plate 31, 54 is a tubular rod which is secured to, and extends upwardly from, the bracket 53 and through a hole in the inner transverse bar 52, 55 is a slotted resilient tube 100 which is secured to the inner transverse bar 52 at its lower end with a flange and surrounds the tubular rod 54 under resilient frictional pressure so as to hold it in any position to which it may be moved, 56 is a solid rod which is mounted to 105 slide in the tube 54 for operating the gripper as will be described, 57 is a nut on the threaded upper end of rod 56 by which the relative movement of the rod 56 and the tubular rod 54, and consequently the relative movement of the rod and 110

the plate 31, is limited, and 58 is a hollow handle with a pin 59 projecting inwardly from its top for engaging a threaded hole in the upper end of rod 56. 60 is a strip of plush or other suitable material at the front edge of the inner transverse bar 52 and 31a is a mating strip on the inner face of the covering plate 31. The two strips keep out the light when the covering plate is raised for opening the dark slide.

10 17 is a compartment in the casing at the rear of the dark slide 1 in which a supply of sensitized paper 15 is mounted on a shaft 16. The compartment 17 is closed at the rear by a vertical wall 14a, at the front by a vertical wall 14, at the top 15 by a horizontal slide 61 and at the bottom by an inclined plate 62. The sensitized paper 15 issues from the compartment 17 through a slot between the wall 14 and the slide 61, and 18 is a strip of plush or the like at the inner end of slide 61 for preventing access of light to the compartment 17. By these means it is possible to open the cover 68 and the covering plate 31 in full daylight without admitting light to the compartment 17. Only that portion of the sensitized paper 15 which is extracted from the compartment 17 past the strip 18 at the inner end of the slide, and taken down to the gripper on the covering plate 31 which will presently be described, is spoiled by the daylight when the dark slide is prepared for operation.

20 30 The paper, after leaving the compartment 17, is first taken up round a saddle 19 at the upper end of the vertical wall 14 and then down along a vertical wall 20 the upper end of which is secured to the saddle. The wall 20 is shaped like the letter U as best seen in Fig. 5, with a horizontal transverse bar 21 at its bottom and two upwardly extending shanks which below the saddle 19 are connected by a transverse filler 22. The vertical walls 14 and 20 are mounted on a horizontal partition 83 at the lower end of the dark slide which, together with the bottom plate 28, forms a compartment for the paper-severing mechanism. 82 are paper guides at both sides of wall 20.

25 35 40 Means must be provided for stretching the paper. In the present instance, this means is a brake for engaging the paper 15 as it moves across the saddle 19. 23 is a brake block at the free end of a brake rod 26 which is fulcrumed in the casing 1 at 27, and 29 is a spring or preferably a pair of springs, which is secured on the rod 26 with its free end bearing on the shoulder of the inner transverse bar 52 on which it is held by the jib 73 of the cover 68 when the cover is closed, so that the brake block 23 is applied to the paper 15 on the saddle 19 under resilient pressure.

55 The gripper will now be described. Mounted on the inner face of the covering plate 31 below the bracket 53 are a pair of trunnions 32 which are held in arms 33 projecting inwardly from a vertical flange of the bracket. 34 is a tubular gripper arm which is mounted to rock about the trunnions 32, 35 is a block of rubber or other resilient material which is inserted at the lower end of the tube, 35a is an arm which projects upwardly from the opposite end of the tube 34, and 36 is a pin by which the arm 35 is connected to the lower end of rod 56, which, as described, is mounted to slide in the tubular rod 54 on the bracket 53, the eye for the pin being slotted to make up for the circular displacement of the arm with respect to the rod which is guided in a straight path in the tube 54. 37 is a U-shaped frame which is secured to the inner face of the covering plate 31 below the bracket 53, 38 is a tubular holder at the rear bar of the frame 37 in

line with the axis of the gripper 34, and 39 is a block of rubber or the like in the holder 38 which is adapted to be engaged by the block 35 on the gripper 34.

40 is a screen for a purpose to be described below, which is mounted to slide on a holder 41 projecting inwardly from the covering plate 31 near its lower end by means of pins 42 projecting through slots in suitable angle brackets 43 on the holder 41. When the covering plate 31 is in its lower final position the lower edge of screen 40 bears on an angle section 83a the horizontal flange of which is secured to the partition 83 by screws 83b in slotted holes 83c for adjusting the section. The vertical flange of the section has its rear face flush with the rear face of the screen 40 and projects into a slot in the partition 83 which on the opposite side is bordered by an extension 44 at the lower end of the vertical wall 20.

90 The mechanism for severing the exposed lower end of the web before it is delivered to the collector 7 or tank 200, Fig. 8, is arranged in the chamber between the bottom plate 28 and the partition 83, and is best seen in Fig. 2. 88 is a vertical shaft which is mounted in the partition 83 near its rear end and 89 is a handle on the end of the shaft which projects upwardly from the partition 83. The handle 89 is located in a niche below the compartment 17 where it is safe from unintentional operation. 90 is an arm which is secured on the lower end of the pin 88, and 29a is a cutter at the end of the arm which is shown as a razor blade by way of example. The cutter 29a is guided by the extension 44 and a bar 45 below the partition 83. 46 and 47 are plate springs at the ends of checks 48 which limit the movement of the arm 90 in opposite directions, the springs 46 and 47 retaining the arm 90 in its final positions by friction after it has performed a cutting stroke.

100 The exposed and severed sheets of paper drop through an opening 27 in the bottom plate 28. 103 is a slide which extends across the opening 27, 104 are a pair of springs at opposite ends of the slide 103 which tend to pull the slide across the opening 27 to close it, and 106 are a pair of pins at opposite ends of the slide 103 which engage in slots 107 in the bottom plate 28. 108 is a dog below the bottom plate 28 which is here shown as an angle section and is secured to the lower ends of the pins 106. 100 is a dog on the collector 7 which engages the dog 108 as the collector is pushed forward along the bottom plate 28 on the strips 105, as fully described in my said copending application Serial No. 567,625. By these means the slide 103 is pushed back against the action of the spring 104 and the opening 27 is fully exposed when the collector is in its final position with respect to the dark slide.

110 Referring now to Fig. 7, the collector is designed substantially as described in my said copending application Serial No. 567,625. The strips 105 at the bottom of the dark slide are engaged by strips 106 at the sides of the collector 140 7. When the collector has been pushed home along the bottom plate 28 of the dark slide the opening 27 is exposed by slide 103 and registers with a similar opening in the top plate of the collector. This last-mentioned opening has been omitted in Fig. 7 which is only intended to show the general arrangement of the collector with respect to the dark slide 1 but not to show the details of the collector which are fully described in my said copending application 567,625. 4 is a 150

lamp bracket in a suitable compartment 5 of the apparatus, 6 is a lamp on the bracket, 8 is an opening in the rear wall of the collector opposite the lamp 6, and 9 is an opening in its front wall 5 in line with the opening 8. Panes of ruby glass or other suitable inactinic material are inserted in the openings 8 and 9.

The sheets of paper which are fed through the dark slide, severed at the bottom of the dark 10 slide, and delivered to the collector 7, move past the opening 8 and obstruct it so that the image of the lamp 6 is not visible in the mirror 10a. As the severed sheets fall into the collector 7 they expose the opening 8 and the image of the lamp 15 6 appears again on the mirror 10. In this manner the image alternately appears and disappears in the normal operation of the feed. If the image appears permanently on the mirror 10, this indicates that the paper is not fed properly or that 20 the supply has become exhausted while, if it disappears permanently, this indicates that the collector is filled, as the last sheet which has been severed cannot move down and permanently obstructs the opening 8. 12 is a receptacle with 25 a hinged bottom flap 13 which is mounted to telescope in the collector 7.

In operation the cover 68 is opened, the slide 30 61 is retracted, a supply of sensitized paper 15 is placed in the compartment 17 and the end of the paper is extracted past the strip 18 at the slide 61. The extracted end is taken up to the saddle 19 along the wall 14, after the covering plate 31 has been raised, round the saddle, and down along the U-shaped wall 20, and threaded 35 through the guides 82 at the sides of this wall. The lower end of the paper is then engaged by the gripper blocks 35, 39 on the covering plate 31. The cover 68 and the covering plate 31 are now closed and the dark slide is ready for operation.

Instead of the fixed compartment 17 with the slide 61 for the reception of the supply of sensitized paper 15, I may provide a casing for the supply which is mounted to rock about trunnions 45 in the side walls of the dark slide and from an opening of which the sensitized paper is extracted, as described in my said copending application Serial No. 567,625.

The block 35 of the gripping mechanism is 50 applied to the paper 15 and in turn applies the paper 15 to the block 39 under the weight of the rod 56 and the handle 58. These parts are comparatively light so that the paper is not subjected to excessive pressure by the blocks which 55 must be avoided as such pressure may produce halo. When it is desired to open the covering plate 31, the handle 58 is raised. This causes the tube 34 to rock about its trunnions 32 until the upper end of its arm 35a engages below the 60 bracket 53 and positively connects the rod 56 to the bracket so that upon further raising the handle 58 the covering plate 31 is positively entrained while at the same time the block 35 is disengaged from the paper 15. The covering plate 31 is opened as far as required for the size 65 to be exposed and the tubular rod 54 moves with the covering plate to which it is connected by bracket 53. When the covering plate is to be closed the handle 58 is depressed and slides down in its tube 54 until the nut 57 at the upper end of the rod 56 bears on the upper end of the tube. The tube, the covering plate and the rod are now 70 positively connected and the block 35 is applied to the paper 15, the paper being gripped by the blocks 35 and 39 and thereby entrained with the

covering plate 31. As mentioned, excessive pressure must not be exerted on the paper between the blocks and the maximum pressure is regulated by adjusting the nut 57. When the covering plate 31 has been arrested by the sill 49 in its lower final position the cutter 29 is operated and the exposed lower end of the paper is dropped into the collector 7.

Margins are formed automatically at the sides of the paper by the guides 82. When the covering plate 31 has been raised the screen 40 moves down by gravity and defines a margin at the upper end of the exposed area. The paper 15 extends down to the level of the cutter 29 and a margin is formed at its bottom the height of which is equal to the depth of the vertical flange of section 83a. The distance through which the screen 44 projects down from the holder 41 on the covering plate 31, must obviously be twice the depth of the vertical flange of section 83a.

Instead of the collector 7 I may attach a desensitizing tank 200 to the lower end of the dark slide 1 as shown in Fig. 8. The tank 200 is filled with a liquid by which the paper is rendered insensitive to daylight to such an extent that it can be removed at actinic light. The action of the desensitizing liquid is so rapid that a piece of paper which has been severed by the cutter 29 and dropped into the sensitizing tank 200, is fully desensitized when it arrives at the opposite end 201 of the desensitizing tank. Therefore it is not necessary to provide means such as a flap at this end for keeping out the light. Preferably curved rails 203 are provided in the desensitizing tank for preventing sticking of the paper to its wall.

Any modern desensitizing liquid may be employed. A suitable liquid is a 1:1000 solution of pinakryptol yellow. This solution while not imparting any color to the paper is so effective that good copies are obtained if the apparatus is not 115 exposed to full day or sun light, i. e. placed in a dark corner of a room, or the blinds of a sunny room are drawn.

Instead of a desensitizing tank a developing tank (not shown) may be attached to the dark 120 slide 1 but as the copies normally require individual developing it is preferable to desensitize them in the manner described whereupon each copy may be developed as required.

I wish it to be understood that I do not desire 125 to be limited to the exact details of construction shown and described, for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:—

1. A dark slide for photographic apparatus in which a flexible web is employed as the bearer of a sensitive solution comprising a covering plate, means for reciprocating said plate mounted on said plate so as to move with respect thereto, a gripper on said covering plate, and means under the control of said reciprocating means for causing the gripper to engage the web upon the descent, and to release it on the ascent, of said covering plate.

2. A dark slide for photographic apparatus in which a flexible web is employed as the bearer of a sensitive solution comprising a covering plate, means for reciprocating said plate mounted on said plate so as to move with respect thereto, a

- gripper on said covering plate, means under the control of said reciprocating means for causing the gripper to engage the web upon the descent, and to release it on the ascent, of said covering plate, and means for positively connecting said plate-reciprocating means to said plate in the web-engaging and in the web-releasing position of said gripper.
5. A dark slide for photographic apparatus in which a flexible web is employed as the bearer of a sensitive solution comprising a covering plate, a rod mounted to slide on said covering plate and projecting from said dark slide, a movable gripping member on said plate operatively connected to said rod, a fixed gripping member, also on said plate, for engaging the web in cooperation with said movable member, and means on said movable member for positively connecting said rod to said covering plate when said movable member is in its web-releasing position.
10. A dark slide for photographic apparatus in which a flexible web is employed as the bearer of a sensitive solution comprising a covering plate, a rod mounted to slide on said covering plate, a gripping member mounted to rock on said plate and operatively connected to said rod, a fixed gripping member, also on said plate, for engaging the web in cooperation with said rocking member, and means on said rocking member for positively connecting said rod to said covering plate when said movable member is in its web-releasing position.
15. A dark slide for photographic apparatus in which a flexible web is employed as the bearer of a sensitive solution comprising a covering plate, a frame on said covering plate, a gripping mechanism for engaging the web mounted on said frame and including a fixed and a movable member, a rod mounted to slide on said covering plate and operatively connected to said movable member at its lower end, the upper end of said rod projecting from said dark slide, a bracket on said covering plate, means on said movable member adapted to engage said bracket and to positively connect said rod to said plate when said movable member is in its web-releasing position, and means for positively connecting said rod to said plate when said movable member is in its web-engaging position.
20. 6. A dark slide for photographic apparatus in which a flexible web is employed as the bearer of a sensitive solution comprising a covering plate, a frame on said covering plate, a gripping mechanism for engaging the web mounted on said frame and including a fixed and a movable member, a rod mounted to slide on said covering plate and operatively connected to said movable member at its lower end, the upper end of said rod projecting from said dark slide, a bracket on said covering plate, means on said movable member adapted to engage said bracket and to positively connect said rod to said plate when said movable member is in its web-releasing position, and means for limiting the movement of said rod with respect to said covering plate in the closing direction of said covering plate.
25. 7. A dark slide for photographic apparatus in which a flexible web is employed as the bearer of a sensitive solution comprising a covering plate, means for reciprocating said plate, a gripper on said covering plate, a tubular rod secured to said covering plate at its lower, and projecting from
- said dark slide with its upper end, a solid rod mounted to slide in said tubular rod with its upper end projecting from said tubular rod, a handle at the upper end of said solid rod, means operatively connecting the lower end of said solid rod to said gripper, and means for limiting the relative movement of said solid and said tubular rod for the movements said solid rod performs for causing said gripper to engage, and for causing it to release, the web.
8. A dark slide for photographic apparatus in which a flexible web is employed as the bearer of a sensitive solution comprising a covering plate, means for reciprocating said plate, a gripper on said covering plate, a tubular rod secured to said covering plate at its lower, and projecting from said dark slide with its upper end, a solid rod mounted to slide in said tubular rod which its upper end projecting from said tubular rod, a tube on said dark slide which engages said tubular rod under resilient pressure, a handle at the upper end of said solid rod, means operatively connecting the lower end of said solid rod to said gripper, and means for limiting the relative movement of said solid and said tubular rod for the movements said solid rod performs for causing said gripper to engage, and for causing it to release, the web.
9. A dark slide for photographic apparatus in which a flexible web is employed as the bearer of a sensitive solution comprising a covering plate, means for reciprocating said plate, a gripper on said covering plate, means under the control of said reciprocating means for causing the gripper to engage the web upon the descent, and to release it on the ascent, of said covering plate, means for severing the exposed lower end of the web, and means for covering the marginal portions of said web against exposure.
10. A dark slide for photographic apparatus in which a flexible web is employed as the bearer of a sensitive solution comprising a covering plate, means for reciprocating said plate, a gripper on said covering plate, means under the control of said reciprocating means for causing the gripper to engage the web upon the descent, and to release it on the ascent, of said covering plate, means for severing the exposed lower end of said web, means on said dark slide for covering a margin at the bottom of the exposed sheet against exposure, and a screen mounted to reciprocate on said covering plate for covering a margin at the top of the exposed sheet against exposure.
11. A dark slide for photographic apparatus in which a flexible web is employed as the bearer of a sensitive solution comprising a covering plate, means for reciprocating said plate, a gripper on said covering plate, means under the control of said reciprocating means for causing the gripper to engage the web upon the descent, and to release it on the ascent, of said covering plate, a partition at the lower end of said dark slide having a slot for the web to move through, an adjustable member on said partition partly projecting into said slot for regulating its width, a cutter arranged below said adjustable member, a bottom plate on said dark slide below said cutter having a slot registering with the slot in said partition, a slide for closing the slot in said bottom plate, means tending to hold said slide in closing position with respect to said slot in said bottom plate, a receptacle for the severed lower ends of the web adapted to be attached to said dark slide below said bottom plate and to be moved into a given final position, and means

adapted to be engaged by said receptacle and to move said slide so as to expose the slot in said bottom plate when said receptacle is in its final position.

5 12. A dark slide for photographic apparatus in which a flexible web is employed as the bearer of a sensitive solution comprising a covering plate, means for reciprocating said plate, a gripper on said covering plate, means under the control of said reciprocating means for causing the gripper to engage the web upon the descent, and to release it on the ascent, of said covering plate, a cutter for severing the exposed lower end of said web, a pair of checks defining the two final positions of said cutter, and means tending to hold said cutter in each of its final positions.

10 13. A dark slide for photographic apparatus in which a flexible web is employed as the bearer of a sensitive solution comprising a covering plate, means for reciprocating said plate mounted on said plate so as to move with respect thereto, a gripper on said covering plate, means under the control of said reciprocating means for

causing the gripper to engage the web upon the descent, and to release it on the ascent, of said covering plate, means for holding a supply of the flexible web in said dark slide, and means arranged intermediate said gripper and said supply-holding means for putting tension on the web.

14. A dark slide for photographic apparatus in which a flexible web is employed as the bearer of a sensitive solution comprising a covering plate, means for reciprocating said plate, a gripper on said covering plate, means under the control of said reciprocating means for causing the gripper to engage the web upon the descent, and to release it on the ascent, of said covering plate, means for holding a supply of the flexible web in said dark slide, a saddle arranged intermediate said supply-holding means and said gripper, a brake block arranged in such relation to said saddle as to bear on the web as it moves about said saddle, and resilient means for exerting pressure on said brake block.
